CORPORATION OF MICHIGAN.

METHOD OF MAKING CHLOROFORM.

1,101,025.

Specification of Letters Patent. Patented June 23, 1914.

Application filed July 26, 1912. Serial No. 711,653.

To all whom it may concern:

Be it known that we, THOMAS GRISWOLD, Jr., and CHARLES J. STROSACKER, citizens of the United States, and residents of Midland, county of Midland, State of Michigan, have jointly invented a new and useful Improvement in Methods of Making Chloroform, of which the following is a specification; the principle of the invention being herein explained and the best mode in which we have contemplated applying that principle, so as to distinguish it from other inventions.

The present invention, relating as indicated to the manufacture of chloroform, has more particular regard to the improvement of the so-called Smith process, as described in U. S. Letters Patent No. 753,325, dated March 1, 1904. Such Smith process, in its entirety, involves the action of heated sulfur upon heated carbon so as to produce carbon bi-sulfid; the action of chlorin on sulfur, so as to produce sulfur chlorid, or di-chlorid; the action of such chlorid upon carbon bi-sulfid so as to produce carbon tetrachlorid; and finally the reduction of carbon tetrachlorid so as to produce chloroform.

The present improvements are concerned more particularly still with the last of the foregoing steps, such steps, as heretofore carried out, being effected by mechanical agitation of the tetrachlorid with water and finely divided iron, or other metal, powdered iron being specifically referred to, in the patent above named.

In order that the temperature of the reaction may be properly controlled, it has been found necessary, in practice, that this finely divided iron should be added in successive portions and not all at once; this because the reaction with the fine iron is so violent that a large amount of heat is generated and excessive amounts of other compounds than chloroform are produced. If, on the other hand, more coarsely granulated iron be used; the reaction is then slow, and although a greater percentage yield is obtained, such slowing down of the reaction so reduces the capacity that but little output is obtained from the apparatus, while a great deal of material is tied up in process. It is also advantageous to add all portions of the charge at one time.

The object of the present invention ac-

cordingly is the elimination of the foregoing difficulties, such invention, to this end, consisting of the steps hereinafter fully described and particularly pointed out in the claims.

The annexed drawing and the following description set forth in detail one approved method of carrying out the invention, such disclosed mode, however, constituting but one of various ways in which the principle of the invention may be used.

In said annexed drawing: the single figure there appearing represents, in more or less diagrammatic form, one type of apparatus suitable for carrying out the operation in question.

Such typical apparatus will be seen to comprise rotatable agitating drum or cylinder 1 provided with trunnions 2 mounted in suitable bearings 3, and further provided with a spaced shell or jacket 4 by means of which the agitating cylinder or drum proper, together with its contents, may be maintained at any desired temperature. The temperature-controlling fluid, usually water, is supplied and withdrawn by means of pipes 5 and 6, respectively, that pass through the left hand trunnion. Instead of such shell 4, forming a water jacket, the drum may be simply rotated in a liquid bath maintained at the proper temperature.

Connecting with the cylinder, or drum, through the right hand trunnion 2, which is made hollow for this purpose, and a connecting pipe 7, is a suction pump 8, by means of which any desired degree of vacuum may be maintained by such drum. This pump is likewise adapted, as will be evident, to remove any vapors from the cylinder as fast as formed. The gases or vapors thus abstracted from the cylinder by the pump are passed through a suitable fractionating apparatus 9, and thence into a condenser 10, from which they are finally collected in a suitable receptacle (not shown).

It should be explained that neither the arrangement of apparatus just described, nor the general method of withdrawing the vapors arising from the reaction in the drum form any part of the present invention, the latter relating to the form in which that portion of the charge consisting of the iron, or other metal, is introduced into said cylinder.

It has been found that by charging the proper amount of fine iron or other finely divided metal, together with a suitable grinding material such, for example, as a quantity of iron balls, small boulders, flints or other hard bodies of the proper specific gravity and treating the charge of carbon tetrachlorid therewith in a rotating reaction vessel of the kind illustrated in the drawing, or equivalent apparatus, wherein a grinding effect may be secured, a very much more satisfactory reduction of the tetrachlorid is secured. For by this method, coarser, larger iron particles may be used to make up a considerable portion of the finely divided iron, and such particles will be gradually reduced in fineness by the action of the balls in the mill so as to permit of a certain control of the reaction, which would not be possible if the same amount of iron, all in a finely divided state, were initially introduced. Not only may a coarser and considerably cheaper grade of iron borings be used in this method, but at the same time the output of the apparatus is raised by an appreciable amount.

The fine particles of iron which are present in a limited amount in the charge, all of which is put in the reaction vessel at one time, immediately react to reduce the tetrachlorid, and as these become spent, more fine particles are produced by the grinding action of the balls upon the coarser particles, and in this way the reaction is maintained in a satisfactory and uniform state of progress until its completion, or until enough of the tetrachlorid has been reduced to warrant distilling the charge, where the distillation is intermittent. The operator is taught by experience to regulate the charge so that by the time the iron is practically spent the major portion of the tetrachlorid will have been converted to chloroform. It is at this stage of the process that the temperature of the bath is raised so as to distil over the product; the latter, passing through the fractionating column, is condensed and collected in suitable containers. With the arrangement of apparatus illustrated in the drawing it is contemplated that such distillation may be carried on practically throughout the entire process of reaction, this being rendered possible by operating under reduced pressure, whereby the chloroform, despite its character as an intermediate reduction product of the tetrachlorid, may be withdrawn continuously.

Other modes of applying the principle of our invention may be employed instead of the one explained, change being made as

regards the process herein explained, provided the step or steps stated by any one of the following claims or the equivalent of such stated step or steps be employed.

65

We therefore particularly point out and distinctly claim as our invention:—

1. The method of manufacturing chloroform, which consists in reducing carbon tetrachlorid by means of a metal in the presence of water, such metal being introduced in the form of particles; and subjecting such particles to a grinding action during the progress of the reaction, whereby they are gradually reduced in fineness.

75

2. The method of manufacturing chloroform, which consists in reducing carbon tetrachlorid by means of iron in the presence of water, such iron being introduced in the form of particles; and subjecting such particles to a grinding action during the progress of the reaction, whereby they are gradually reduced in fineness.

80

3. The method of manufacturing chloroform, which consists in reducing carbon tetrachlorid by means of iron in the presence of water, at least a portion of such iron being introduced in the form of relatively coarse particles; and subjecting said particles to a grinding action during the progress of the reaction, whereby they are reduced in fineness.

85

4. The method of manufacturing chloroform, which consists in agitating water, carbon tetrachlorid, and iron together, at least a portion of such iron being in the form of relatively coarse particles, and grinding material being included therewith, whereby said particles are gradually reduced in fineness as the agitation continues.

100

5. The method of manufacturing chloroform, which consists in agitating water, carbon tetrachlorid, and iron together, at least a portion of such iron being in the form of relatively coarse particles, and a quantity of hard bodies being included therewith, whereby said particles are gradually reduced in fineness as the agitation continues.

105

6. The method of manufacturing chloroform, which consists in agitating water, carbon tetrachlorid, and iron together, at least a portion of such iron being in the form of relatively coarse particles and a quantity of iron balls being included therewith, whereby said particles are gradually reduced in fineness as the agitation continues.

110

Signed by us this 23rd day of July, 1912.

THOMAS GRISWOLD, Jr.
CHARLES J. STROSACKER.
